TUNER FOR RADIO RECEIVING SETS

Albert S. Wells and Jesse H. Clark, Chicago, Ill.,
assignors to Wells-Gardner & Company, Chi-
cago, Ill., a corporation of Illinois

Application March 1, 1937, Serial No. 123,378

6 Claims. (Cl. 250—20)

An object of this invention is to provide an improved form of tuning device for radio receiving sets which can be operated to tune in a desired station by a single continuous operation of the operator's finger.

Another object is to provide in such a tuner means for setting each button of the tuner for a desired station without disassembling any parts of the set.

Still another object is to provide a tuner of the type described above which can be used in connection with a receiving set having a manual tuning dial particularly of the projector type wherein the tuner is in the form of a ring which surrounds the dial.

These and other objects as will hereinafter appear are accomplished by this invention which is fully described in the following specification and shown in the accompanying drawings in which:

Figure 1 is a partial front elevation of a chassis removed from its cabinet showing one embodiment of the invention with an operator's hand in position to tune the set to a given station;

Fig. 2 is a similar view of the tuner only after it has been turned to the desired station;

Fig. 3 is a partial top plan of the chassis;

Fig. 4 is a partial enlarged section on the line 4—4 of Fig. 3 showing the front mounting plate removed together with the automatic tuning mechanism;

Fig. 5 is a partial enlarged section as viewed on the line 5—5 of Fig. 3;

Fig. 6 is an enlarged vertical elevation on the broken line 6—6 of Fig. 1;

Fig. 7 is a section on the broken line 7—7 of Fig. 6 showing one of the tuning fingers between the vertical stops in the act of tuning the set with the automatic tuner;

Fig. 8 is a similar view showing the end stop which prevents rotation of the tuner below a predetermined point;

Fig. 9 is an enlarged section on the line 9—9 of Fig. 6;

Fig. 10 is a partial perspective of a portion of the automatic tuning dial showing a button and its tab in their normal inoperative positions;

Fig. 11 is the same showing the button depressed and the tab rotated about the axis of the button to a releasing position;

Fig. 12 is a view of the parts showing the button further depressed so as to permit of adjustment of the button and its associated tuning finger for a given broadcasting station;

Fig. 13 is a partial section on the line 13 of

Fig. 2 showing the button depressed in the operation of tuning the set;

Fig. 14 is a partial section on the line 14—14 of Fig. 12;

Fig. 15 is an enlarged section on the line 15—15 of Fig. 13 showing the tab in the position of Fig. 10;

Fig. 16 is a similar section showing the tab in the position of Fig. 11;

Fig. 17 is a similar section on the line 17—17 of Fig. 14;

Fig. 18 is a partial enlarged section on the line 18 of Fig. 5 showing the limit stop in adjusted position; and

Fig. 19 is the same in process of being adjusted.

The embodiment illustrated shows a set having the usual manual means for adjustment over its entire range together with a means for quickly and accurately tuning the set for a number of stations whose positions have been predetermined.

Briefly the set may be tuned in the usual way by hand by rotating a gang condenser A (Fig. 3), the stations tuned being shown on a ground glass screen by light from a dial lamp B which projects light through a photographic film C on a mirror D which reflects the image on a ground glass dial E which is viewed by the operator. This forms no part of the present invention and hence will not be described in detail.

The automatic tuner is mounted to rotate about the dial E and is designed to quickly and accurately tune in any one of a number of previously selected stations whose positions have previously been located on the automatic tuner and a button therefor set on the tuner as will hereinafter be explained.

The chassis as illustrated comprises a main frame 20 which is pressed from sheet metal and on which is yieldingly mounted a plate 21 (Figs. 4 and 6) by means of rubber buffers 21^a to which is secured a casting 22 which has a tubular extension 23 through which passes light from the mirror D on its way to the screen E. This screen is enclosed in a rubber gasket 24 which is held in place by means of an annular finishing strip 25 which is retained by screws 26.

A front mounting plate 27 is secured to the plate 21 by means of screws 28 and to the casting 22 by means of a screw 29. This front mounting plate carries most of the parts which go to make up the present automatic tuner. This tuner comprises among other things a ring gear 30, a tuning ring 31 which has bosses 31^a by means of which it is secured to the ring gear by means of

screws 31^b, and a drum 32 which is secured to bosses 30^a on the ring gear by means of screws 30^b.

The ring gear 30 (Fig. 5) is mounted on four grooved rollers 33 each of which is rotatably mounted on a screw 34 affixed to the front mounting plate. The ring gear rests upon the grooved rollers and is guided by the upper two, the ring gear having gear teeth of reduced width which pass through a groove in the rollers as shown in Fig. 6.

A substantially non-extensible flexible cord 35 passes substantially one and one-half times around the drum 32 and has one end secured thereto by means of a short spring 36 (Fig. 5) while the other end is secured thereto by means of a relatively long spring 37, the latter particularly tending to maintain the cord under a uniform tension at all times. This cord passes around a grooved tuning spool 38 which is keyed on a shaft 39 which is suitably journaled preferably in a ball-bearing housing 40 carried by the front mounting plate 27. The cord 35 may also pass over an idler 41.

The ring gear 30 meshes with a gear 42 which drives a pinion 43 which meshes with a gear 44 which acts through a sleeve 44^a to drive an arm 45 which has an extension 45^a which is adapted to lie between a lug 46 and a short leaf spring 47 (Figs. 5, 6 and 9). As will be seen from Figs. 6 and 9, the lug 46 and the spring 47 are carried by sheaves 48 on the shaft 49 of the gang condenser A. The sleeve 44^a is rotatable about a stud 44^b which is carried by the front mounting plate 27 and is in alignment with the shaft 49. This provides a convenient flexible drive to the gang condenser which permits the front mounting plate to be removed. Upon reassembling, the extension 45^a is readily inserted between the lug 46 and the spring 47, when these parts are in proper alignment.

Thus it will be seen that the set is manually tuned by rotating the shaft 39 by means of the tuning knob 39^a (Fig. 1). At the same time, the photographic film C is rotated in front of the dial lamp B by means of a wire rope 50 (Fig. 4) which passes around a drum 51 on a shaft 52 which carries the film C and which is tensioned by means of an idler sheave 53 carried on a lever 54 under the action of a spring 55.

The automatic tuning feature will now be described. The purpose of this is to enable the operator by a single movement of his hand to bring the tuning dial 31 to rest at the exact point at which it is in tune for a given station. To do this we have provided the tuning dial with a plurality of buttons 56, which are located at intervals in the tuning dial 31, each to be marked with a suitable disk 57 with the call letters of a station which it is desired to tune with that button, the disk being covered by means of a transparent cover 58 of Celluloid or the like.

Each button is in alignment with the shaft of a tuning element 59 which is rotatably mounted in a boss 60 on the ring gear 30, there being an extension 59^a passing through the button to which it is keyed and to which it is secured by means of a spring clip 61 engaging within an annular groove in the extension. A spring 62 serves to hold the button normally in the outer position, as shown in Fig. 6.

The tuning element 59 has at its opposite end a lever 63 which terminates in a cylindrical tuning finger 64. Each tuning element 59 carries a locking arm 65 the outer surface of which is

serrated while an inner arcuate surface 66 (Fig. 5) is provided with complementary serrations so that each lever arm 63 is capable of adjustment through quite a wide range and of being secured in any of those adjusted positions by the engaging serrations. Inasmuch as the point at which the tuning dial will stop depends upon the position of the finger 64, it will thus be seen that each one of the tuning elements is capable of stopping the dial at many points.

Referring now to Fig. 6, it will be seen that the button 56 and its associated tuning element 59 are normally maintained in an out position by means of the spring 62. To bring a particular element into operation, the operator pushes in the button and then swings the tuning dial so as to bring this button to the lowermost position. As he does so the finger 64 encounters a stop which will now be described. The stop is shown in Fig. 7 and consists of two opposing yielding stop blades 67, 68 which are rotatably mounted on pins 69, 70 at the bottom and top respectively (Figs. 6 and 7) and are yieldably urged toward each other by means of a spring 71 so that they normally rest against lugs 67^a, 68^a. The distance between the blades 67 and 68 is but slightly greater than the diameter of the cylindrical finger 64 and the sides of these blades which are encountered by the finger 64 when depressed are inclined in both directions so that no matter from which direction the finger proceeds toward these blades, it depresses the first one and is stopped by the other, the first blade then promptly springing into place behind the finger, as shown in Fig. 7. If, therefore, the tuning element 59 has been accurately set for the reception of a given broadcasting station, that station will be received the instant the tuning dial is turned so as to bring the tuning finger of that tuning element between the stop blades 67, 68.

As long as the button remains depressed with one of the fingers 64 between the blades of the stop, the set cannot be tuned by means of the tuning knob 39^a. Also, for reasons which will later be described, the set is completely detuned as long as the button 56 remains depressed.

An adjustable stop for the tuning dial is provided by the stop member 72 (Figs. 5, 8, 18 and 19) which is eccentrically mounted upon a shaft 73 which passes through the ring gear 30 and has an extension 74 the edge of which is serrated for engagement with the serrated edge of the opening 75. The member 72 is normally held retracted in the position shown in Fig. 18 by means of a spring 76. This stop member 72 is longer than the fingers 64 so that it engages the stop blade 67 as it reaches the end of the swing of the dial in one direction and engages the stop blade 68 when it reaches the end of its swing in the reverse direction. This stop member is set once and need not be reset. This stop member lies immediately back of a wide spacer 77 (see Fig. 1) which at its lowest point comes to the end of the swing of the tuning dial in either direction, and thus corresponds to a wave length of the highest or the lowest permissible by the set.

With none of the buttons 56 depressed the set can be tuned by hand in the usual way. It is desirable, however, that while using the automatic tuner the set shall be inoperative so that it will not pick up the stations through which it passes before reaching the desired station. In order to do this we have added a metal ring 78 (Fig. 13) which is secured to the back of the

tuning dial 31 but insulated therefrom. A brush 79 which is insulated by insulation 79^a from the front mounting plate 27 is connected through a suitable insulated lead 80 with a portion of the tuning circuit, not shown. Each button carries a metal member 81 which is keyed thereto and rotatably held thereon by a collar 56^a which is cemented in place. The metal member 81 has a tab 82 which in the position shown in Fig. 10 is thrown to the left. The member 81 extends down so that when the button is depressed for the purpose of tuning as shown in Fig. 13, the member 81 makes contact with the ring 78 with the result that the tuned circuit is then grounded through the member 81, the spring 62 and the ring gear 30. It will thus be seen that a convenient method is thus provided for silencing the set during the time the button 56 is depressed.

The method of adjusting each tuning element will now be described. This is shown in Figs. 10 to 17, inclusive. The tab 82 normally remains at the left hand side as shown in Fig. 10. The member 81 engages the ring 78 and hence prevents the member 56 from being depressed far enough to permit the locking arm 65 to pass out of engagement with the toothed arcuate portion 66, and consequently, the tuning finger 64 remains fixed with respect to the tuning dial. During the operation of setting each tuning finger 64 for a given station, it is necessary that the arm 65 be permitted to swing freely until the desired setting is reached after which this arm will then become locked with the serrated arcuate portion 66. In order to do this the tab 82 swings about the axes of the button 56 and the element 59, as shown in Fig. 11. This permits the inner end of the member 81 to pass the inner edge of the ring 78 with the result that when the button is now depressed, as shown in Fig. 14, the set will not be shorted but will continue to play if a station is tuned in. At the same time, the button 56 is permitted to be further depressed as is also the element 59, thereby freeing the arm 65 from the serrated arcuate portion 66.

If with the parts in the position shown in Fig. 14 the finger is held between the stop blades 67, 68, as shown in full lines in Fig. 7, the set can be tuned by hand by turning the tuning knob 39^a (Fig. 1) until that particular station is sharply tuned in. The operator then releases the button and the spring will return the element 59 to its normal position in which the arm 65 will be locked by the serrated arcuate portion 66. This button is then permanently locked in this position by holding the button in the position shown in Fig. 11 which is a mid-position during which time the tab 82 can be moved from the full line position of Fig. 11 to the dotted line position. The tab is provided with a small depression into which the operator may place a pencil or other sharp object which serves to swing the tab from one position to the other. In moving the tab from the dotted line position to the full line position, the button must also be held in the intermediate position of Fig. 11. Fig. 12 shows the button and its associated tab in the fully depressed position for tuning.

By this arrangement of tuning fingers, each covering a wide range, any desired station in the broadcast band will fall on some one of the tuning fingers.

Having now selected the particular station, the

operator also selects a disk 57 showing the call letters of that station and places it in the button as shown in Fig. 6 with a transparent cover 58. This provides a smooth surface for the operator's finger during the operation of tuning and keeps the disk 58 from becoming soiled.

Thus it will be seen that a very simple and efficient means is provided for tuning in a given broadcasting station by a simple continuous movement of the operator's finger. While we have shown and described but a single embodiment of this invention, it is to be understood that it is capable of many modifications. Changes, therefore, in the construction and arrangement may be made which do not depart from the spirit and scope of the invention as disclosed in the appended claims.

We claim:

1. In a radio receiving set, a chassis frame, a front plate of shallow depth removably carried thereby, a rotatable tuning condenser carried by the chassis frame, and means carried by the plate and removable therewith for tuning the condenser, said means having a flexible driving connection to the condenser which is readily separable from the condenser on removing the front plate from the chassis frame, said driving means including spaced driving members on one element, one of which is yieldable and a tongue on the other element adapted to lie between the spaced members.

2. In a radio receiving set, a radio tuning element, a dialing member rotatably mounted in the set, a stop, a plurality of buttons yieldably carried by the dialing member, each button being adapted to be depressed by an operator and having a finger adapted to engage the stop only when the button is depressed to stop the rotation of the dialing member, said finger being eccentric to the axis of the button, each button being rotatable about its axis when depressed beyond a given point to permit the dialing member to be turned to tune in a desired station within the limits of movement of the finger, and means for locking the button which in one position prevents the button from being depressed far enough to be rotated into another adjusted position and in another position permits the button to be depressed for this purpose.

3. In a radio receiving set, a radio tuning element, a dialing member rotatably mounted in the set, a stop, a plurality of buttons yieldably carried by the dialing member, each button having a finger adapted to engage the stop only when the button is depressed to stop the rotation of the dialing member, said finger being eccentric to the axis of the button, each button being rotatable about its axis to permit the dialing member to be turned to tune in a desired station within the limits of movement of the finger, and means for locking each button so that its finger lies in any one of a number of adjusted positions, said means comprising a tab rotatably carried by each button, said tab when in a normal position preventing the depression of the button beyond a predetermined point and permitting its depression beyond said point for the purpose of readjusting the setting of the finger when in another position.

4. In a radio receiving set, a radio tuning element, a dialing member rotatably mounted in the set, a stop, a plurality of buttons yieldably carried by the dialing member, each button having a finger adapted to engage the stop only when the button is depressed to stop the rotation of

the dialing member, said finger being eccentric to the axis of the button, each button being rotatable about its axis to permit the dialing member to be turned to tune in a desired station within the limits of movement of the finger, and means for locking each button so that its finger lies in any one of a number of adjusted positions, said means comprising a tab rotatably carried by each button, said tab when in a normal position preventing the depression of the button beyond a predetermined point and permitting its depression beyond said point for the purpose of readjusting the setting of the finger when in another position, the button when depressed acting to silence the set when the tab is in the normal position but without silencing the set when the tab is in the other position. 5 10 15

5. In a radio receiving set, a radio tuning element, a dialing member rotatably mounted in the set, a stop, a plurality of buttons yieldably carried by the dialing member, each button having a finger adapted to engage the stop only when the button is depressed to stop the rotation of the dialing member, said finger being eccentric to the axis of the button, each button being rotatable about its axis to permit the dialing member to be turned to tune in a desired station within the limits of movement of the finger, and means for locking each button so that its finger lies in any one of a number of adjusted positions, said means comprising a tab rotatably carried by each button, said tab when in a normal position

tion preventing the depression of the button beyond a predetermined point and permitting its depression beyond said point for the purpose of readjusting the setting of the finger when in another position, said tab being of metal and making electrical contact with a portion of the set so as to silence the same when the tab is in a normal position but not when the tab is rotated to the other position where adjustment is permitted.

10 6. In a dial telephone type tuning control mechanism for radio receivers, in combination, a casing mounted for rotation and operatively connected to a tuning element of said receiver, 15 a multiplicity of plungers arranged peripherally around said casing, and projecting therethrough, said plungers terminating in fingers projecting inwardly, a pair of yieldable gates arranged to be entered by said fingers in depressed position 20 only, to provide a positive stop against rotation of said casing in either direction, one of said plungers normally biased to forward position and having a finger of greater length than the others, and of sufficient length to abut against one of 25 said gates when said plunger is in forward position and of sufficient width to prevent closure of the other gate therebehind, whereby to form a stop limiting the rotation of said casing to 360°.
